UNITED STATES PATENT OFFICE.

JOHN S. CLARK AND WASHINGTON HARRIS, OF PHILADELPHIA, PA.

IMPROVEMENT IN FIRE-DOORS FOR STOVES.

Specification forming part of Letters Patent No. 40,326, dated October 20, 1863.

To all whom it may concern:

Be it known that we, JOHN S. CLARK and WASHINGTON HARRIS, of the city of Philadelphia, in the State of Pennsylvania, have invented a new and useful Improvement in the Fire-Doors of Stoves; and we do hereby declare that the following is a full, clear, and exact description of the construction and operation of the same, reference being had to the accompanying drawings, making a part of this specification, in which—

Figure 1 is a front view, and Fig. 2 a central vertical section, of a stove door having our said improvement applied thereto, like letters of reference indicating the same parts when in both figures.

The object of our invention is to enable the attendant or operator to readily protect the mica or transparent portions of the feed or fire door of a stove from becoming obscured or blackened by the smoke or soot which is generated in starting or kindling a fire in the stove.

It consists, substantially as hereinafter described and specified, in so applying and securing the mica sheet or sheets, which are in general use for producing the transparent portions of the feed or fire doors of stoves, that the same may be readily covered or protected from the access of the smoke or soot which arises from the fire at the pleasure of the attendant or operator without opening the said door.

In the drawings, A is the door, and B the mica applied thereto. In the present instance the door A is made in the ordinary form, with four openings around its center. The central portions, containing the openings, are depressed, so as to receive a circular disk, c, which also has four openings, and a secondary disk, d, having corresponding openings, riveted to the inner side of the same, so that their said openings shall be opposite to each other, respectively, and so, also, as to leave a thin space between the two disks c d for the introduction of the mica B.

The inner disk, d, is also provided with a central stem or journal, e, which passes through a corresponding hole in the main body of the door A, and is there secured by a pin, f, so that the disks c and d, containing the mica B, may be turned to the right and

left alternately sufficiently far to bring the transparent portions either directly opposite the openings in the main portion of the door A or directly behind the solid portions which are between the said openings, substantially as represented in the drawings.

A small projection, g, is cast on the rim of the outer disk, c, which serves as a handle for giving motion to the disk, and on the inner side of the rim of the inner disk, d, there is also a small projection, h, which traverses a short concentric groove, i, in the depressed portion of the main portion of the door, the two together operating as a stop to limit the motions of the disk.

It will be readily seen that an attendant can at any time protect the mica B from becoming obscured or blackened by the smoke or soot without opening the door by simply turning the disk c so as to bring the mica or transparent portions of the same behind the solid or closed portions of the main part of the door, and that an opposite movement of the disk will restore the transparent condition of the door.

We wish it to be understood that we do not intend to confine our invention to the particular mode described of constructing the same, as it is obvious that the mica may be arranged so as to remain stationary, while an inner disk may be made to cover and uncover it, as occasion may require, to produce the same result, and that a square slide may be arranged so as to operate to protect the mica in the same manner; but—

Having fully described our improvement and shown what we believed to be the best mode of carrying it out in practice, what we claim as new therein of our invention, and desire to secure by Letters Patent, is—

The arrangement of the mica in the fire or feed door of a stove provided with a movable disk or slide and suitable openings, so that the said mica can be either covered or exposed, as occasion may require, without opening the said door, substantially as described, for the purpose specified.

JOHN S. CLARK.
WASHINGTON HARRIS.
